Primary Examiner—Philip S. Hyder*Assistant Examiner*—R. L. (Ulm) Cody*(74) Attorney, Agent, or Firm*—Calfee, Halter & Griswold, LLP(57) CLAIM

The ornamental design for a storage container, as shown and described.

DESCRIPTION

FIG. 1 is a perspective view of a storage container of the new design;

FIG. 2 is a right side view of the storage container of FIG. 1;

FIG. 3 is a left side view of the storage container of FIG. 1;

FIG. 4 is a top view of the storage container of FIG. 1;

FIG. 5 is a front view of the storage container of FIG. 1;

FIG. 6 is a rear view of the storage container of FIG. 1; and,

FIG. 7 is a bottom view of the storage container of FIG. 1.

The portions of the Figures shown in phantom lines are not part of the claimed design, but are for illustration purposes only.
